UNITED STATES PATENT OFFICE.

ARTHUR M. HUNGERFORD, OF SEATTLE, WASHINGTON.

TRACTOR BED.

Application filed February 1, 1927. Serial No. 165,117.

The invention is an adjustable bed for hospital or other uses which is provided with devices for raising or stretching parts of the body or holding any part of the body in any suitable position.

5 The object of the invention is to provide a bed having all of the necessary appliances for treating all types of injuries to the body.

Another object of the invention is to provide a bed having means for readily raising 10 either end.

Another object of the invention is to provide adjustable means on a bed for holding and stretching a limb.

15 A further object of the invention is to provide suitable adjustable means on a bed for readily raising and stretching an arm.

A further object of the invention is to provide an adjustable bed of the type described, which may readily be placed over 20 or attached to another bed.

And a still further object of the invention is to provide an adjustable bed of the type described, which is of a simple and economic 25 construction.

With these ends in view the invention embodies, a tubular frame having a rectangular horizontal frame adjustably held thereto, 30 longitudinal and transverse rods adjustably attached to the said frame, attachments on the said rods and suitable means for raising or lowering the said rectangular shaped frame.

35 Other features and advantages of the invention will appear from the following description, taken in connection with the drawings, wherein:

Figure 1 is a view showing the bed as it 40 would appear ready for use.

Figure 2 is a detail taken on line 2-2 of Figure 1 with the corner post omitted and showing the arrangement of the ratchet and drum and the attachment for holding them 45 to the post.

Figure 3 is a detail showing means for attaching the adjustable frame to a bed by clamping the legs together.

Figure 4 is a detail showing means for 50 placing the frame on a bed having corner posts by cutting off the tops of the post and placing a socket over them.

In the drawings the device is shown as it 55 would be made, wherein numeral 1 indicates

the vertical members of the said frame, 55 numeral 2 the horizontal members and numeral 3 the rectangular shaped frame that is adjustably held on the said vertical members.

The members 1 may be of any suitable size 60 or length and may be made of pipe or tubing or solid bars, as may be desired. At the upper ends of the members 1 are connections 4 that are screwed to the top of the posts 1 by a threaded member 5. These connections hold 65 the horizontal longitudinal rods 2, which are held in sockets 6 by set screws 7 and also horizontal transverse rods 8, which are held in sockets 9 by set screws 10. On the posts 1 at one end of the frame are also hinged members 11 which may readily be attached to the 70 posts and which are provided with sockets 12 in which a horizontal transverse bar 13 may be held by set screws 14. The outer end of the bar 13 is provided with a support 15 which is held in a socket 16 and at the lower 75 end of which is a telescoping member 17 by which its length may readily be adjusted. On the bar 13 is also a socket 18 having a pulley 19 supported therefrom over which a weight may be held through a cord which 80 may be attached to a limb or any other part of the body. On the vertical posts 1 at the opposite end are also sockets 20 in which a frame 21 is adjustably and pivotally held 85 which may be moved upward or downward with the lower bar adaptable to move outward to rest upon the rectangular frame 3 to form a head or back rest at any suitable inclination. On the posts at this end are also 90 hinged sockets 22 that form bearings for a square transverse shaft 23 upon which drums 24 may be mounted and which may also be supplied with a ratchet 25 and a pawl 26 to engage the ratchet and hold the drum in any 95 suitable position. The outer end of the shaft 23 may be provided with a crank 27 by which it may readily be rotated. At the upper ends of the posts 1 at this end are also connections 9 which hold the ends of the rods 2 100 and also a transverse rod 28 that is similar to the rod 8 at the opposite end. Adjustable sockets 29 with pulleys 30 suspended from them are slidably mounted on the shaft 28 and these cooperate with similar sockets on the rod 8 and the drums 24 to operate blocks 30 through cords as shown. It will be observed that the blocks 30 are provided with

hooks for gripping the frame 3 so that the frame may readily be raised or lowered by turning the crank 27.

Sockets 31 are slidably mounted on the bars 8 and 28 and support a central longitudinal bar 32 upon which smaller transverse bars 33 are slidably mounted through sockets 34. Some of these bars are provided with slidable sockets 35 having pulleys 36 suspended from them for raising and stretching arms or the like and some of these bars are provided with slidable sockets 37 having swivel sockets 38 attached to them in which another bar 39 may be slidably held and other sockets 35 may be slidably mounted upon this bar so that it will be possible to grip and hold any part of the body in any suitable position.

The rectangular frame 3 may be made of any suitable material, which may also be of any suitable shape and may be provided with members 40 that are pivotally attached to clamps 41 by pins 42 as shown. It will be observed that the clamps 41 may be firmly clamped around the posts 1 by screws 43 and the pins 42 may be loosened when it is desired to raise the frame so that the frame may be adjusted to any suitable angle. It will be observed that either end of the frame 30 may be raised, as shown by the dotted lines.

The super frame which rests upon the posts 1 may be placed over a bed and the frame 3 and the head rest 21 may be omitted. The super frame may readily be adjusted 35 to the length and width of the bed and the posts 1 held to the posts of a bed, which are indicated by the numeral 44 by clamps 45 which have hinged inner members 46 to fit any sized post.

40 It is also understood that the upper portion of the frame only may be used in combination with a bed having vertical corner posts and the corner posts, which are indicated by the numeral 46 and shown in Figure 4 may be cut off. A socket 47 may then be provided which has a threaded shank 48 that screws into the portion 5 of the connection 4 and is provided with an opening in the lower end which may be placed over the 45 upper ends of the posts 46. The bar 13 and the members at the opposite end of the frame may then be attached to the bed posts if desired.

It will be understood that changes may be 55 made in the construction without departing from the spirit of the invention, one of which changes may be in the use of material of any other shape, another may be in the combination or arrangement of any of the 60 parts and still another may be in the use of connections of any other suitable designs.

The construction will be readily understood from the foregoing description. To use the device it may be assembled as shown 65 with the rod 13 extending to either side and

the rods 33 also extending in either direction. It will be observed that by arranging these parts in any suitable manner it will be possible to hold or stretch any portion of the body.

Having thus fully described my invention, what I claim as new and desire to secure by Letters Patent, is:

1. In a device of the class described, a frame constructed with four vertical posts forming the corners and positioned similar to the posts at the corners of a bed, transverse members extending across the end posts, longitudinal members extending across the upper ends of the posts, split clamp sockets adjustably attaching the transverse and longitudinal members to the posts, another longitudinal member extending across the transverse members between the two former longitudinal members, split longitudinal member to the transverse members, a plurality of arms attached to the said latter longitudinal member by split sockets and normally resting on the said former longitudinal members, attaching devices mounted on the said arms by split clamp sockets, a rectangular shaped frame horizontally positioned between the said posts and attached to the posts by split clamp sockets, 95 said frame forming the frame of a bed upon which a spring may be placed, a plurality of hooks suspended from the said attaching devices and adapted to engage a spring or auxiliary frame that may be placed upon the bed, a suitable windlass attached to the head posts for raising or lowering the said hooks, and an adjustable head rest upon the head posts.

2. In a tractor bed of the class described, 105 a plurality of vertical posts forming the corners similar to the posts of a bed, transverse members extending across the posts at the ends, longitudinal members extending across the posts at the top, combination 110 sockets comprising two circular openings perpendicularly disposed in relation to each other, split at the sides and provided with bolts for drawing the sides together to clamp the sockets around an object, attaching the said horizontal transverse and longitudinal members to the said vertical members and adaptable to slide vertically and to be clamped upon the said vertical members when in position, intermediate transverse and longitudinal members also extending across the said former members, combination sockets, adjustably attaching the intermediate transverse and longitudinal members to the said former member, rods 115 forming arms also attached to the said longitudinal and transverse members by the said combination sockets and therefore adaptable to be moved toward either side, suitable attached devices slidably mounted 120 125 130

on the said rods by the said combination forming the main frame of a bed upon
5 sockets, a transverse member extending which a spring or the like may be placed,
across the said vertical members at one end an adjustable frame adaptable to be used
and extending beyond the limits thereof, as a head rest attached to one end of the
combination sockets adjustably and slidably 15 said device, and a suitable windlass with
attaching the said transverse member to the suitable tackle for raising and lowering an
said vertical members, a substantially horizontal frame positioned between the said auxiliary frame that may be used upon the
vertical members and attached to them by said horizontal frame.
10 the said combination sockets, said frame

In testimony whereof I affix my signature.
ARTHUR M. HUNGERFORD.
